UNITED STATES PATENT OFFICE

165,018

FIRE-EXTINGUISHING FOAM PRODUCING UNIT

Louis E. Mitchison, Baltimore, Md., assignor to
National Foam System, Inc., West Chester, Pa.,
a corporation of Delaware

Application June 28, 1951, Serial No. 15,697

Term of patent 14 years

(Cl. D16—2)

To all whom it may concern:

Be it known that I, Louis E. Mitchison, a citizen of the United States and a resident of Baltimore, city of Baltimore, State of Maryland, have invented a new, original, and ornamental Design for a Fire-Extinguishing Foam Producing Unit, of which the following is a specification, reference being had to the accompanying drawing, forming a part thereof, wherein:

Figure 1 is a perspective view of a fire-extinguishing foam producing unit, showing my new design; and

Figure 2 is a fragmentary rear elevational view of that part of the unit shown in full lines in Fig. 1 with portions of the foam projecting tube broken away for convenience of illustration.

The dominant feature of my design resides in the portions shown in solid lines.

I claim:

The ornamental design for a fire-extinguishing foam producing unit, substantially as shown and described.

LOUIS E. MITCHISON.
